DESIGN FOR SUN GOGGLES

Edward McGlynn, New York, N. Y.

Application September 2, 1938, Serial No. 79,730

Term of patent 3½ years

To all whom it may concern:

Be it known that I, Edward McGlynn, a citizen of the United States of America and resident of the city of New York, county of New York, and State of New York, have invented a new, original, and ornamental Design for Sun Goggles, set forth in the following specification, reference being had to the accompanying drawing, forming part thereof.

In the drawing:

Figure 1 is a front elevational view showing

sun goggles embodying my new design; Figure 2 is a plan view of Figure 1; Figure 3 is a view taken similarly to Figure 2 showing the sun goggles in their folded position and Figure 4 is an enlarged sectional view as seen from the plane 4—4 on Figure 3.

I claim:

The ornamental design for sun goggles, as shown.

EDWARD McGLYNN.
